UNITED STATES PATENT OFFICE.

KAMENOSHIN TSURUOKA, OF HONOLULU, TERRITORY OF HAWAII.

BEAN-CUTTER.

1,252,744.

Specification of Letters Patent.

Patented Jan. 8, 1918.

Application filed January 21, 1916. Serial No. 73,484.

To all whom it may concern:

Be it known that I, KAMENOSHIN TSURUOKA, a subject of the Emperor of Japan, Empire of Japan, residing at Honolulu,

5 Territory of Hawaii, have invented new and useful Improvements in Bean-Cutters, of which the following is a specification.

This invention relates to bean cutters, and it has for its object to produce a simple 10 and efficient device, whereby green beans may be cut lengthwise in two or more pieces and crosswise into as many parts as may be desired in a simple, rapid and satisfactory manner.

15 A further object of the invention is to produce a bean cutting device of the character described whereby the beans may be cut without the fingers of the operator coming in contact with the cutting devices.

20 A further object of the invention is to produce a device of the character described in which the cutting devices will be conveniently accessible and removable for sharpening and other purposes.

25 With these and other ends in view which will readily appear as the nature of the invention is better understood, the same consists in the improved construction and novel arrangement and combination of parts 30 which will be hereinafter fully described and particularly pointed out in the claims.

In the accompanying drawings has been illustrated a simple and preferred form of the invention, it being, however, understood 35 that no limitation is necessarily made to the precise structural details therein exhibited, but that changes, alterations and modifications within the scope of the claims may be resorted to when desired.

40 In the drawings.—

Figure 1 is a side elevation of a device constructed in accordance with the invention.

Fig. 2 is a top plan view of the same.

45 Fig. 3 is an end view.

Fig. 4 is a vertical sectional view taken on the line 4—4 in Fig. 1.

Fig. 5 is a vertical sectional view taken on the line 5—5 in Fig. 3.

50 Fig. 6 is a perspective detail view of the plunger or follower detached.

Fig. 7 is a perspective detail view showing the cutter carrying frame detached.

55 Fig. 8 is a sectional detail view on a larger scale of the lower end portion of the hopper and related parts.

Corresponding parts in the several figures are denoted by like characters of reference.

In the construction of the improved bean cutting device there is included a hopper 60 comprising downwardly convergent side members 15 and vertically disposed end members 16, the convergent side members being sufficiently spaced apart at their lower ends to permit the passage of a bean. When 65 the hopper is constructed of wood a lining or a partial lining of sheet metal may be used, as indicated at 17, but this, of course, is optional.

Hingedly connected with the inner faces 70 of the side members 15 near the lower ends thereof are doors or bottom members 18, said doors being connected with the side members 15 by hinges 19. The doors 18 are adapted to open downwardly against the 75 tension of actuating springs 20, the upwardly swinging movement of said doors being obstructed by stop members 21 on the inner faces of the end members of the hopper. The doors or bottom members will thus 80 be normally maintained by the action of the springs in an approximately horizontal position, closing or obstructing that portion of the hopper in which they are mounted, it being understood that said doors are positioned some distance above the lower edges 85 of the side members of the hopper.

The end members 16 are extended downwardly below the side members of the hopper and are provided with legs or supporting members 22. Said end members are also provided adjacent to the lower ends of the side members 15 with slots 23 for the passage of a frame 24 which is slidably supported in said slots adjacent to the lower 95 edges of the side members 15. Said frame, which is constructed of metal, is of approximately rectangular shape, relatively long and narrow, and the ends of said frame are provided with apertures 25 for the passage 100 of threaded stems 26 between which the knives or cutters 27 are stretched, said stems being provided with kerfs or slots 28 for the reception of the cutting members, which latter are connected with the stems by transverse pins or cotters 29. Nuts 30 that engage the threaded stems and abut on the end portions of the frame may be utilized 105 for tightening or tensioning the cutting members as well as for the purpose of securing the stems in position in the frame.

Auxiliary transversely disposed cutting

members 31 may be used, said auxiliary cutting members having notches 32 to engage the cutting members 27.

The end members 16 are provided with upwardly extending arms or brackets 33 supporting one or more cross bars 34 in which apertures are formed for a vertically movable stem or handle 35 which is actuated in an upward direction by a spring 36, said 10 stem being provided at its upper extremity with a knob or handle 37. The lower end of the stem 35 carries a plunger which is composed of two wings or leaves 38 that are hingedly connected with each other, as well 15 as with the stem 35, so as to be capable of swinging independently with respect to said stem. A spring 39 which is interposed between the leaves 38 serves to force the lower ends of said leaves apart from each other 20 and in the direction of the downwardly convergent side members 15 of the hopper, the outwardly swinging movement of said leaves being, however, limited by downwardly extended portions 40 of the stem 35, said portions 25 40 lying adjacent to the outer faces of the leaves.

The parts of the device are so arranged and proportioned that when properly assembled the knives or cutting members 27 of which one or more may be used will lie beneath and adjacent to the opening between the lower extremities of the side members 15 of the hopper, said cutters, of which two have been shown in the drawings, being 30 preferably spaced equally with respect to the lower inner edges of the side members 15. The plunger stem will normally be maintained in a raised position by the spring 36. When a bean pod is dropped into the 35 hopper it will fall on the door members 18 beneath the plunger, and when the latter is pressed downwardly against the tension of the spring 36, the leaves 38 which are pressed apart from each other by the spring 40 39 will first engage the inclined walls of the side members of the hopper, and will thereby be forced together against the tension of the spring 39, thus exerting downward pressure on the bean pod, the latter being forced 45 downward between the doors 18 which will be forced open against the tension of their actuating springs 20 due to the pressure exerted by the plunger. If the bean pod, which is almost invariably the case, is more 50 or less curved longitudinally, it will be straightened out by the conjoint action of the leaves 38 which will first engage the portions of the pod that lie in engagement with the oppositely inclined walls of the 55 hopper; the leaves being gradually forced together so as to exert straight downward pressure against the bean pod which latter, 60

having thus been straightened out will be forced downward upon the cutting members, whereby it will be cut lengthwise in as many 65 parts as may be desired, the number of parts being governed by the number of cutters employed, and the parts being also severed crosswise in as many pieces as may be desired by the auxiliary cutters 31. It is obvious 70 that this operation may be performed far more quickly than by the use of an ordinary kitchen knife and in a much cleaner and more sanitary manner. The device is simple in construction, and owing to 75 the fact that the cutter carrying frame may be readily assembled it may be easily maintained in a clean and sanitary condition. The cutting members may also be easily removed for sharpening or repairs, as may be 80 occasionally needed.

Having thus described the invention, what is claimed as new, is:

1. In a device for cutting beans and the like, a hopper having downwardly converging side walls and a cutting member located in the path of material passing through the hopper, in combination with a plunger comprising a stem, and leaves hingedly connected with said stem and with each other. 85

2. In a vegetable cutter of the class described, a hopper having downwardly convergent side members spaced apart at their lower ends, a cutting member supported in the path of material forced through the 95 hopper, a spring actuated obstructing member mounted above the lower extremity of the hopper and capable of swinging downwardly, and an upwardly spring-actuated plunger comprising a stem and leaves 100 hingedly connected therewith and with each other.

3. In a vegetable cutter of the class described, a hopper having downwardly converging side members spaced apart at their 105 lower ends, a cutting member supported in the path of material forced through the hopper, a spring actuated obstructing member mounted above the lower extremity of the hopper and capable of swinging downwardly, and an upwardly spring-actuated plunger comprising a stem and leaves hingedly connected therewith and with each other, and a spring interposed between said leaves whereby the free edges of the leaves 110 are forced outward with respect to each other. 115

In testimony whereof I affix my signature in presence of two witnesses.

KAMENOSHIN TSURUOKA.
